BINDER TAB FOR WEB ROLLS

Albert J. Horton, White Plains, N. Y., assignor to
R. Hoe & Co., Inc., New York, N. Y., a corporation of New York

Application February 8, 1935, Serial No. 5,667

13 Claims.

(Cl. 242—58)

This invention relates to means for holding the free end of the web of a web roll, for a printing machine or other machine operating upon a web, against the body of the roll, and more particularly to a tab structure which is secured to both the body of the roll and the web end.

Previous to making a web join between the running web of an expiring running web roll and the web of a replacement roll, adhesive is applied on the outside of the free end of the web of the replacement roll which is then rotated at the speed of the running web, moved into close proximity therewith, and at the desired time, the said running web is pressed against the replacement roll, whereupon the adhesive portion adheres to the running web and after severing the web from the expired roll, the new web is drawn forward into the machine.

Mechanical devices have been used to hold the free web end against the body of the replacement roll while it is being rotated to make a web join, whereby the web end is released at the moment a web join is made, and paper tabs have been used, which have gummed portions adapted to be pasted to both the body and web end portions of the web roll. Such tabs are usually formed from paper and the material has a weakened portion between the points of contact with the roll body and web end to facilitate the separation thereof when a web join is being made.

It has been found that although tabs made with a weakened portion will release the web end when making a web join, it is difficult to apply them to the roll so as to hold the web end down properly without tearing them and causing the web end to be released prematurely.

According to the invention, tabs are provided which have no weakened central structure but which are of substantially equal strength throughout their material structure, and due to their peculiar formation are adapted to be easily separated or torn at chosen points to provide quick and positive release of the web end.

It is the principal object therefore to provide tabs which have full natural strength throughout their material structure and to form same in a manner whereby they may be easily separated or torn to release the web end from the body of the roll when a join is made.

It is a further object to provide tabs which can be applied to the roll without the exercise of especial care on the part of the machine operator.

With the above and other objects in view which will appear as the description proceeds, the in-

vention resides in the forms, and in the details of construction hereinafter described.

Several embodiments of the invention are illustrated in the accompanying drawings wherein:

Figure 1 is a front elevational view showing a portion of a web roll with a rectangular ring form of tab structure joined to the free web end and the body of the roll;

Figure 2 is an enlarged front view of the rectangular ring form of tab structure;

Figure 3 is a similar view to Figure 1, showing a circular ring form of tab structure;

Figure 4 is an enlarged front view of the circular ring form of tab;

Figure 5 is a view similar to Figure 1, showing a V-shaped form of tab structure;

Figure 6 is an enlarged front view of the V-shaped tab structure;

Figure 7 is an enlarged view similar to Figure 1, showing another form of tab applied to the free web end and body of the roll;

Figure 8 is an enlarged front view of one surface of the tab shown in Figure 7 with an adhesive indicated on the central portion thereof;

Figure 9 is a view showing the opposite surface of the tab shown in Figure 8 with an adhesive indicated at the ends of the tab;

Figure 10 is a slightly modified structure of the tab shown in Figure 8 with the adhesive at the central portion thereof;

Figure 11 is a view showing the opposite surface of Figure 10 with an adhesive indicated at the ends of the tab;

Figure 12 is a diagrammatic view showing a web roll supporting reel with an expiring web roll and a replacement roll thereon, also showing means to rotate the replacement roll, a brush to press the running web against the replacement roll when making a web join, and a web severing means;

In Figure 12, one method is illustrated for mounting web rolls which includes a reel 25, rotatably mounted on a support 26 and adapted to support a plurality of web rolls. In the particular arrangement shown, an expiring web roll is indicated at 27 and a replacement roll is indicated at 28, with the running web of the expiring roll moving close to the replacement roll.

Also combined with the roll mounting is a driven endless belt 29 which accelerates the replacement roll to the speed of the running web, and a brush member 31 which is pivotally mounted at 32 and is adapted to be moved against the running web to move the said web into engagement with an ad-

hesive portion on the free web end of the replacement roll to make a web join. Means to sever the web after a join is made is also indicated at 33.

5 As soon as the running web adheres to the adhesive portion on the replacement web end, it is important that the web end is immediately freed from engagement with the body of the roll. This is accomplished by providing a tab means which 10 is adapted to be secured to both the free web end and the body of the roll in a manner which will cause the said tab structure to be torn or otherwise separated as soon as a predetermined strain is applied thereto such as by the pulling action 15 of the web end when the running web engages the adhesive on the replacement roll.

The tabs herein disclosed may also be used with machines wherein means are provided for applying adhesive to the running web instead of to the 20 end of the web of the replacement roll.

In Figures 1 and 2, a ring form of tab is shown which has very desirable qualities. In this form, some suitable material such as paper is stamped into the form of a rectangular ring 34 and has 25 dabs of adhesive 35-35 applied to two opposite corners thereof, one corner of which is secured to the body B of the replacement roll at the central portion thereof, while the opposite corner is secured to the web end W of the said roll. An adhesive is also applied along the end of the web 30 as indicated at A, except for a limited space where the accelerating belt 29 will engage the roll 28.

During the period that the said replacement roll 28 is rotating, the free end W is adequately 35 held against the body of the roll, but as soon as the running web is brought into contact with the adhesive A on the web end, the strain exerted upon the tab will tend to pull one end away from the other and will rupture or tear the tab latterly 40 across the corners, as indicated by the dot and dash lines in Figure 2.

The circular tab structure 36, shown in Figures 3 and 4, is applied in the same manner as the rectangular ring with one adhesive portion 37 45 engaging the body B of the roll and another adhesive portion 37 engaging the web end W. When a join is made, the tab is torn along the portion indicated by the dot and dash lines in Figure 4.

When either of the tabs shown in Figures 1 to 4 50 is used, the action of pulling the web end away from the roll when it adheres to the running web tends to straighten the sides of the ring and thereby stress only the inside edges on each side, which quickly starts tears that immediately sever 55 the tab.

In Figure 5, another form of tab structure is shown applied to a web end having a fish-tail configuration as shown at 38, and in which two tabs 39-39 are provided, one at each end of the 60 fish-tail portion. Each of the tabs 39-39 is of substantially V-formation and has an adhesive 41 applied over approximately one half of its length on one side and an adhesive 42 applied over approximately one half of its length on the 65 opposite side, as best shown in Figure 6. When securing these tabs in place, one adhesive portion is secured to the body B of the roll, while the other adhesive portion is secured to the web end W, and when a web join is made, the tabs are 70 torn vertically across the central portions thereof. An adhesive A is also applied to the web end as in the previously described structures.

In Figures 7, 8, and 9, another arrangement is shown wherein a tab 46 is formed with a central 75 peak portion 48 having an adhesive 47 on its

front surface and two end portions 48-48 projecting sideward from said central portion and having adhesive 49-49 applied on their rear surfaces. The adhesive ends are secured to the body of the roll and the central adhesive portion is secured to the free end of the roll, the edge of the said free end being shaped to conform with the peak formation of the tab. When a join is made, the tab will be torn along the lines indicated by the outer boundaries of the adhesive portion 47. 10

To further assist in the tearing of this form of tab, the ends may be formed so as to project angularly upward as shown at 48a-48a in Figures 10 and 11, to provide sharp V-shaped portions at 50-50. The adhesive portions will be applied in 15 the same position as previously described for Figures 8 and 9.

It will be observed that in each of the tab structures disclosed, there are no weak portions in the material structure such as perforations, slits, or 20 the like, but that the full strength of the material structure is maintained throughout the tab.

It will be understood that the invention may be embodied in other specific forms without departing from the spirit or essential attributes thereof, 25 and it is therefore desired that the present embodiments be considered in all respects as illustrative and not restrictive, reference being had to the claims rather than to the foregoing description to indicate the scope of the invention. 30

What I claim is:

1. A tab member for application to a roll from which a web is to be fed to a machine, formed of material having substantially equal strength throughout its material structure, one portion 35 having adhesive thereon for pasting it to the body of the roll and another portion having adhesive thereon for pasting it to the free end of the web of the roll, in a manner whereby it will hold the free end against the body of the roll 40 even when it is rotated rapidly; said tab member being so constructed that the said one portion extends from and out of alignment with the other portion and is easily separated therefrom at a point intermediate the portions to release the 45 free end of the web from the body of the roll when the said free end is brought into contact with a running web and adheres thereto.

2. A tab member for application to a roll from which a web is to be fed to a machine, formed of 50 material having its opposite edges parallel and having substantially equal cross sectional strength throughout its length, one portion of said tab member having adhesive thereon for pasting it to the body of the roll and another 55 portion of said tab member having adhesive thereon for pasting it to the free end of the web of the roll, in a manner whereby said tab will hold the free end against the body of the roll even when it is rotated rapidly; said tab member being 60 so constructed that the said one portion extends from and out of alignment with the other portion and is easily separated therefrom at a point intermediate the portions to release the free end of the web from the body of the roll when the said free 65 end is brought into contact with a running web and adheres thereto.

3. A tab member for application to a roll from which a web is to be fed to a machine, formed of material having its opposite edges parallel, and 70 having an equal width and strength throughout its length, one portion of said tab member having an adhesive thereon for pasting it to the body of the roll and another portion of said tab member having an adhesive thereon for pasting it to 75

the free end of the web of the roll in a manner whereby it will hold the free end against the body of the roll when it is rotated rapidly; said tab member being so constructed that the portions 5 are joined by an intermediate integral bent portion and the said one portion is easily separated from the said other portion at the bent portion to release the free end of the web from the body of the roll when the said free end is brought into 10 contact with a running web and adheres thereto.

4. A V-shaped tab member for application to a roll from which a web is fed to a machine, and having an adhesive portion at each side of said V, one adhesive portion being arranged to be pasted 15 to the body of the roll and the other adhesive portion being arranged to be pasted to the free end of the web of the roll to thereby hold said free end against the body of the roll, said tab being arranged in a manner, whereby upon engagement 20 of a running web with an adhesive on the free web end, the tab is torn at the point of the V.

5. A V-shaped tab member for application to a roll from which a web is fed to a machine, and having an adhesive applied along one surface of 25 one side of the V, and other adhesive applied along the opposite surface of the other side of the V, one adhesive portion being arranged to be pasted to the body of the roll and the other adhesive portion being arranged to be pasted to the free end of the web of the roll to thereby hold said free end against the body of the roll, said tab being arranged in a manner, whereby upon engagement 30 of a running web with adhesive on the free web end, the tab is torn at the point of the V, and the web end is released from the roll.

6. The combination with a replacement web roll for a printing machine, of a tab member comprising a strip having an inverted V-shaped central portion and two end portions offset from 40 said central portion, an adhesive on the upper surface of said central portion and an adhesive on the opposite surface of said end portions, the central adhesive portion being pasted to the free end of the web of the roll, and the end adhesive 45 portions being pasted to the body of the roll to thereby maintain said free web end in contact with the body of the roll; said roll being rotatably supported and said tab being arranged in a manner, whereby upon engagement of a running web 50 with an adhesive portion on the free web end, the tab is torn and releases the web end from the body of the roll.

7. A tab member for application to a roll from which a web is to be fed to a machine, said member being formed of material having substantially equal tear resisting strength throughout its area, one portion of said member having means thereon for securing it to the body of the roll, and another portion having means thereon for securing 55 it to the free end of the web of the roll to hold the same together, said member being formed with said portions being joined by a bent portion integral with each, to insure separation of the same at an intermediate place in the bent portion and between said portions.

8. Means for application to a roll from which a web is to be fed to a machine, said means being formed of material having equal tear resisting strength throughout, and including a portion

having means thereon for securing it to the body of the roll, and a portion having means thereon for securing it to the free end of the web of the roll, said portions being connected intermediate opposing ends of said securing means thereon at 5 an angle to each other to insure separation thereof at the angle, when the said free end of the web is joined to a running web.

9. In combination with the free end of the web of a web roll, means formed of material having 10 substantially equal tear resisting strength throughout its material structure, and including a portion extending along and secured to the edge of the free end of the web, and a portion extending from said first portion and secured 15 to the body of the roll, said portions being disposed at an angle to each other to form a corner-like point at their meeting place to insure separation thereat, when the said web end is joined to a running web. 20

10. In combination with the free end of the web of a web roll, a tab formed of material having substantially equal tear resisting strength throughout its structure, and including a portion extending over and secured by an adhesive 25 to the edge of the free end of the web, and a portion extending out of alignment from said first portion and secured by an adhesive to the body of the roll, whereby when the web end is joined to a running web the tab will tear intermediate 30 the adhering portions. 30

11. In combination with the free end of the web of a web roll, a tab formed of material having substantially equal tear resisting strength throughout its structure, and including a portion 35 extending over and secured by an adhesive applied on one side of the tab to the edge of the free end of the web, and a portion extending out of alignment from said first portion and secured by an adhesive applied on the other side 40 of the tab. 40

12. In combination with an inverted V shaped free end of the web of a web roll, a tab formed of material having substantially equal tear resisting strength throughout its structure, and including a first portion extending over and secured by an adhesive to the underside of the edge of one side of the inverted V shape of the web end, and a second portion extending from said 45 first portion and secured by an adhesive to 50 the upper surface of the body of the roll, said first and second portions extending out of alignment from each other and being separated when the web end is joined to a running web by the tearing of the tab intermediate the said portions. 55

13. A tab for securing the free end of a web of a web roll to the roll comprising a strip of material having substantially equal tear resisting strength throughout its structure and being constituted by portions disposed out of alignment with each other, means to secure one portion to the web end, means to secure the other portion to the roll, said tab extending across the edge of the web end and the portions of which separate, when the web end is joined to 60 a running web, by tearing on a line substantially parallel to the line of run of the running web and between the portions. 65

ALBERT J. HORTON.
